CLOCK CASING

Monte L. Levin, New York, N.Y., assignor to General Time Corporation, Stamford, Conn., a corporation of Delaware

Filed Nov. 8, 1967, Ser. No. 9,323

Term of patent 14 years

(Cl. D42—7)

FIG. 1

FIG. 2

FIG.3.

FIG.4.

FIG. 1 is a front elevational view of a clock casing showing my new design;

FIG. 2 is a rear elevational view;

FIG. 3 is an elevational view from the right of FIG. 1; and

FIG. 4 is a top plan view.

The broken line showing of a clock face and hands is for illustrative purposes only.

I claim:

The ornamental design for a clock casing, substantially as shown and described.
